UNITED STATES PATENT OFFICE.

STANISLAUS LESMIESKI, OF ROCHESTER, NEW YORK.

DESIGN FOR A SMOKING SET.

58,193.

Specification for Design. Patented June 21, 1921.

Application filed September 11, 1920. Serial No. 409,709. Term of patent 3½ years.

To all whom it may concern:

Be it known that I, STANISLAUS LESMIESKI, a citizen of Poland, residing at Rochester, in the county of Monroe and State of New York, have invented a new, original, and ornamental Design for a Smoking Set, of which the following is a specification reference being had to the accompanying drawing, forming part thereof.

The figure is a perspective view of the smoking set, showing my invention.

I claim:

The ornamental design for a smoking set as shown.

In testimony whereof I affix my signature.

STANISLAUS LESMIESKI.
